(57) **CLAIM**

The ornamental design for a hybridization cartridge, as shown and described.

DESCRIPTION

FIG. 1 is a perspective view of a hybridization cartridge showing our new design;

FIG. 2 is a top plan view thereof;

FIG. 3 is a side view thereof, the opposite side view being identical;

FIG. 4 is an end view taken from above the device as depicted in FIG. 2;

FIG. 5 is a bottom plan view thereof; and,

FIG. 6 is an end view taken from below the device as depicted in FIG. 2.

The features illustrated in broken lines in the figures do not form a part of the claimed invention.
